UNITED STATES PATENT OFFICE.

JOSIAH R. CRENSHAW, OF STARRSVILLE, GEORGIA.

PLOW-FOOT.

945,020.

Specification of Letters Patent.

Patented Jan. 4, 1910.

Application filed May 11, 1909. Serial No. 495,265.

To all whom it may concern:

Be it known that I, JOSIAH R. CRENSHAW, a citizen of the United States, residing at Starrsville, in the county of Newton and 5 State of Georgia, have invented a new and useful Plow-Foot, of which the following is a specification.

This invention has relation to a plow foot and it consists in the novel construction and 10 arrangement of parts as hereinafter shown and described.

The object of the present invention is to provide a foot of the character indicated which is adapted to carry a shovel or plow 15 plate and a sweep. The parts of the foot being so formed and arranged that the said plate and sweep are positively held in adjusted position when located upon the foot.

In the accompanying drawings: Figure 1 20 is a perspective view of the plow foot. Fig. 2 is a vertical sectional view of the lower portion of the same. Fig. 3 is a transverse sectional view of the plow foot cut on the line 3—3 of Fig. 2. Fig. 4 is a bottom 25 plan view of a portion of the plow foot.

The plow foot consists of a sole block 1 which is provided in its sides with recesses 2. The lower ends of the side pieces 3 of the plow standard are secured in the recesses 30 2 by means of a pin 4 which passes transversely through the said pieces 3 and the intermediate portion of the sole 1. The sole 1 is provided at its rear end with a series 35 of curved serrations 5. The side pieces are provided at their forward edges with serrations 6. A plow plate 7 is provided with an elongated slot 8 and the upper end of the said plate is adapted to engage the serrations 6 provided at the forward edges of 40 the side pieces 3. A block 9 is located between the lower portions of the side pieces 3 and is provided with an elongated opening 10 through which a bolt 11 passes. The said bolt is secured at each end portion to 45 the side pieces 3 of the plow standards. The said block 9 is provided at its lower end with a projection 12 which lies behind the rear edges of the side pieces 3 and which is provided upon its forward side with a 50 series of serrations 13. The said projection is also provided at each side with shoulders 14 which are adapted to have contact with the rear edges of the side pieces 3 or approximately so.

The opening 10 in the block 9 is provided with a series of serrations 15, between which

the bolt 11 may be seated, and which forms a means for adjustably securing the block 9 to the standard 3.

From the above description it is obvious 60 that by loosening the bolt 11 the block 9 may be shifted into position between the sides 3 so that the projection 12 thereof may be brought toward or moved away from the sole block 1, thus the space between the said projection 12 and the sole may be increased or diminished to receive a sweep as indicated at 17 of any breadth. When the sweep 17 is positioned between the block 9 and the sole block 1 a heel bolt 18 is passed through the 70 slot 8 and through the space between the lower portions of the side pieces 3 and through the said plate and a beveled washer is placed on the lower end of the said heel bolt and secured thereon by means of a nut 75 20 screwed upon the lower end of the said heel bolt. It will also be seen that prior to securing the heel bolt 18 as above indicated the shovel 7 may be shifted longitudinally along the lower portions of the side pieces 3 80 of the plow standards so that the forward edge of the said shovel may project to a greater or less degree in front of the forward end of the sole block 1. Also it will be seen that by seating the bolt 11 in any space between adjacent serrations 15 at the upper 85 end of the opening 10 in the block 9, the said block may be adjusted and secured with relation to the side pieces of the standard. By reason of the fact that the serrations 5 provided in the sole of the block are curved the 90 said serrations are adapted to receive a sweep the intermediate portion of which is straight or curved. Thus it will be seen by such an arrangement that when the plow plate and the sweep are adjusted in their 95 relative positions means is provided for positively holding the said sweep and plate in such adjusted position irrespective of the strain or rough use to which such parts are usually subjected, during the operation of plowing. It will also be seen that a detachable sole block is provided and when one sole becomes worn to such an extent as to be valueless it may be readily removed from 100 the lower portions of the side pieces 3 and a new one put in in its stead.

Having described my invention what I claim as new and desire to secure by Letters Patent is:

1. In combination with a plow standard, a sole block attached thereto and having a se-

ries of serrations, a block adjustably attached to the standard and having a projection lying behind the standard, said projection being provided with a series of serrations.

2. In combination with a standard, a sole block attached thereto and having a series of serrations, a block adjustably attached to the standard and having tongues adapted to enter serrations provided in the standards, the last said block having a projecting portion lying behind the rear edge of the standard and provided with a series of serrations.

3. A standard having upon its forward end a series of serrations, a plow plate having its rear edge engaging said serrations, a

sole block attached to the standard, and having a series of serrations, a block adjustably attached to the standard and having a portion projecting behind the rear edge of the standard and provided with a series of serrations, a sweep held by the serrations of the two blocks and a heel bolt passing transversely through the said plate and the said sweep.

In testimony that I claim the foregoing as my own, I have hereto affixed my signature in the presence of two witnesses.

JOSIAH R. CRENSHAW.
